ATTORNEY

UNITED STATES PATENT OFFICE.

JOSEPH B. SINGER AND ARTHUR B. LEVY, OF NEW YORK, N. Y.

FOLDING DISPLAY BOX.

Application filed March 23, 1921. Serial No. 454,607.

To all whom it may concern:

Be it known that we, JOSEPH B. SINGER, a citizen of the United States, and resident of the city, county, and State of New York, and ARTHUR B. LEVY, a citizen of the United States, and resident of the city of New York, county and State of New York, have invented certain new and useful Improvements in Folding Display Boxes, of which the following is a specification.

The present invention relates to improvements in folding display boxes of the type wherein the telescoping cover and container portions cooperate with each other, the said portions being made of fibrous material such as pasteboard. Hitherto there has been some wastage of stock in stamping or cutting the blank or blanks which are subsequently bent to form the parts of the box. This waste or pieces left over in the sheet from which the blank or blanks are cut is usually useless for box making purposes, still it must be considered by the manufacturer in computing costs with the result that it affects the ultimate cost of the product.

Another item that heretofore affected the cost to produce these boxes has resided in the decorative printing on the exterior of the box.

Coming now to the present invention the general object thereof is first the provision of a folding display box, the portions of which may be cut or stamped from a sheet of fibrous material, as pasteboard, without any appreciable wastage of stock, and which may be readily printed in one color in a single operation, and having a false bottom which may, with or without a display, be used with the box and readily inserted therein, and which may be printed in single and preferably several colors, without requiring handling of the other parts of the box.

To these ends the invention resides in the provision of a primary blank having the form of a parallelogram and constructed so that when folded one face thereof will provide the entire outer surfaces of the cover and container portions of the box, and in the provision of secondary blank for forming a false bottom separate and distinct from the other portions of the box and also constructed so as to have the form of a paral-

lelogram and to be incorporated with a correspondingly shaped display panel if so desired.

Another object is to adapt the false bottom to provide one of the walls, and a lock for another wall or walls of the box.

Other objects will appear and be better understood from that embodiment of the invention of which the following is a specification, reference being had to the accompanying drawings forming a part thereof, and in which:

Figure 1 is a plan view of the blank from which the cover and container portions of one embodiment of the invention are formed, from which it will also be seen that the blank is in substantially that of a parallelogram;

Figure 2 is a view similar to Figure 1 showing one embodiment of the false bottom, from which it will also be seen that the blank is in substantially that of a parallelogram;

Figure 3 is a vertical longitudinal section showing the parts arranged in display position;

Figure 4 is an enlarged detail longitudinal section of one end portion of the container;

Figure 5 is an enlarged vertical cross section of the container, and

Figure 6 is a perspective showing the box in closed position.

The blank *a* from which the cover and container portions are formed is substantially a parallelogram in contour and herein shown as provided with an outer face or surface, the texture of which is fine and suitable for taking a relatively high grade of printing as compared with the opposite face, which is shown uppermost in Figure 1, and which is relatively coarse. In constructing the blank so that the finer surface thereof will be exposed and constitute the entire outer face of the box when the same is in display position, and also when folded, suitable slitting and hinging is provided so as to lay out the blank into several sections. Of these the section 5 comprises the base of the cover portion *b* of the box, and is connected by crease hinges, 6, 6, to the section 7, 7, which, when turned upwardly, and at right angles to section 5, as viewed in Figure 1, will constitute the side walls of the

cover portion, and thus expose on the exterior of the cover that surface of the blank having the finer texture. The end walls 8 and 9 are connected by crease hinges 10, 10, 5 to the opposite ends of section 5, and when turned upwardly the same surface is exposed as described in connection with the side walls 7, 7. The tabs or flaps 11, 11 and 12, 12, connected by the crease hinges 13, 13, 10 to the end walls 8 and 9 serve to connect the said end walls and side walls together when the cover *b* is in set-up position.

In the drawings we have shown sections 14 and 15 as being connected by crease hinges 15 16, 16 to the sections 7, 7 of the side walls in order that the said sections 14, 15 may be turned over the inner faces of the sections 7, 7, when the same are in set-up position, and thereby provide the open ended pockets 20 for the reception of the tabs or flaps 11 and 12 when these are bent inwardly, so as to align with the crease hinges 6—6. The extensions or ledges 17 and 17 connected by crease hinges 19, 19 to the section 14, 15 are 25 adapted to be turned at right angles to the sections 14 and 15, and engage with up-struck lugs 20, 20 arranged on the marginal portions of section 5, and thereby cooperate to provide a lock for the pockets to prevent 30 accidental displacement of the side walls or disconnection of the end walls.

The section 21 constitutes the base or bottom of the container portion *c* and the side walls 22 and 23 which are connected by 35 crease hinges 24, 24 to section 21, and also the end wall 25 which is connected to one end of section 21 by crease hinge 26 are bendable so that when the container portion is in set-up position the outer surface thereof will 40 be similar to the outer surface previously described in connection with the cover portion *b*. The tabs or flaps 27 and 28 are connected by the crease hinges 29, 29 to the end wall 25, and are turnable into alignment with 45 the crease hinges 24, 24 when the end wall 25 is in set-up position. The sections 30 and 31 connected by crease hinges 32, 32 to the sections 22 and 23 of the side walls are adapted to be turned downwardly when the 50 sections 22 and 23 are bent upwardly into set-up position, and thereby cooperate with the said sections 22 and 23 to provide pockets for the reception of the tabs 27 and 28 when arranged as previously described. The 55 connection between the cover and container portions is such, in the action of opening the box as to require the operator to turn the cover until the same is inverted and disposed underneath the container section, in 60 which position the container section is readily insertable into the cover and assumes an inclined position therein, and bears on one end of the cover, as shown in Figure 3.

In the embodiment shown the tongue 33 65 is connected by the crease hinge 34 to the

end wall 9 and to any convenient portion of the cover portion, as for instance, the central portion of section 21, by crease hinge 35. The tongue results from the presence of a pair of converging slits 36 and 37, which 70 extend from the ends of the crease hinge 34 to the ends of the crease hinge 35, so that when the cover is lifted from the container a continued movement of the cover disposes the parts in the position shown in Figure 3, 75 and finally the parts move to display position, as shown in Figure 3.

It will be observed that the opening caused by the movement of the tongue from between the slit 36, 37 when the parts are in display 80 position is closed by the body portion 38 of the false bottom D having the contour of a parallelogram and cut or stamped from a single sheet of fibrous material. The area of the portion 38 approximates that of the bottom 21 so as to nicely fit within the container. It will be noted by reference to Figure 1 that the sections 30 and 31 of the container are provided with extensions 39 and 40, similar to the extensions 17 and 17 85 of the side walls 14, 15. The crease hinges 41, 41, which connect the sections 39, 40 to the sections 30, 31, permit the said sections 39, 40 to be turned outwardly when the said sections 30, 31, are in set-up position so as 90 to bear on the bottom 21. When the false bottom D is arranged as shown in the drawings, the sections 39 and 40 are interposed between the bottoms *c* and D so that false bottom D functions as a lock for the side 100 walls. The flaps 42 and 43 connected by the crease hinges 44, 44 to the sections 30, 31 of the container side walls are bendable inwardly when the said sections are in set-up position, and thus provide an end wall for 105 the container opposite to the end wall 25. A pocket is provided for the tabs 42 and 43, which pocket also provides the outer and inner faces of said end wall, and the sides thereof are made up of the sections 44' 110 and 45' connected one to the other by the crease hinge 46, and to the portion 38 by the crease hinge 47. When the portion 38 is disposed in the container *c* and the tabs 42 and 43 turned into alignment, the section 44' 115 is turned upwardly, and over the outer faces of the tabs, and the section 45 turned downwardly and over the inner faces of said tabs. To prevent disengagement of the parts of the end wall just described, a lock is provided in the form of an extension 48 connected by a crease hinge 49 to the section 45 and an up-struck lug 50 at one end of portion 38. Thus it will be seen that the false bottom functions as a lock for one or more of the walls of the 120 container portion.

In display boxes of the type described, a display panel is usually provided to project upwardly from one end of the box, 125 130

and which may be folded thereinto when the box is closed. As shown in the drawings, such a panel may be provided when desired by the provision of the panel 51 which is connected by the crease hinge 52 to the section 53, and is connected by the crease hinge 54 to the portion 38. With this construction section 53 forms a base for supporting panel 51 when arranged in display position, and upon which panel 51 may be turned downwardly and disposed over the interior of the container when the box is closed.

It is to be observed that the construction of the cover and container portions is such that the box is made from a blank of a shape corresponding substantially to a parallelogram. Thus, by laying out on a sheet of pasteboard a plurality of blanks of a size necessary to make a box or container of desired size, this plurality of blanks can be so arranged as to get the maximum amount of useful material out of the same, without waste or with a minimum of waste.

25 The false bottom D is such that the cutting or stamping of these parts from a sheet of fibrous material such as pasteboard is accomplished by arranging a plurality of these parallelograms on another sheet in such a way as to get the maximum amount of useful material without waste or the minimum of wastage.

The arrangement of the main or primary blanks each of substantially parallelogrammatic shape, on one sheet, and the similar arrangement of the secondary or false bottom blanks on another sheet provides for a maximum usefulness of the stock of material.

40 It is to be further observed that the decorative printing usually applied to display boxes may be applied to the cover and the container portions of the structure of this invention in one operation. This arrangement of parallelogrammatic blanks next to each other is also permissible when the printing operation is carried out. By arranging the main or primary blanks next to each other on a press, all these can be printed at once, and the greatest amount can be printed together without any waste space on the press. Similarly, with the false bottom. It is usual to print the cover and container portions of cartons of the 45 class to which this invention relates, in a single color and in instances where a display panel is used to print the same in multicolor. The present construction readily lends itself to effect the carrying out of this procedure with a minimum of cost; in that the parts are disconnected and each in the form of a parallelogram and each therefore printable without requiring handling of both at the same time; 55 the contour of each further permitting the

arrangement of a maximum number thereof to be operated upon at one time in printing press.

In cases where the dummy bottom or display have multicolors and the cover and 70 containers have one color, and both of these are on one press, then it is necessary to use the press when printing multicolor on the comparatively small display surface, and all those portions, as box and cover, 75 are dead space, hence the expense is correspondingly great. But where the primary blanks are printed at once, and the secondary blanks are printed separately, much saving in the cost of printing results. 80

Although we have shown and described an ideal form of the invention, it is to be understood that we are not to be limited to the construction shown and described in connection with this application it being 85 obvious that the device is susceptible of any modifications within the scope of the appended claims.

We claim:

1. A folding display box comprising a 90 body and a cover adapted to telescope together in the closed position of the box, said body having a section cut therefrom, said section having hinged connection both with the cover and with the body and 95 adapted to connect such cover and body for relative swinging movement of the cover about the lower forward end of said body with reference to the display position of the body, said section and cover acting to 100 support the body in an inclined position with the front end of the body resting in the cover, and a supplementary bottom fitted in said body and covering the void made by said hinged section. 105

2. A folding display box comprising telescoping cover and container portions and a flexible connection between said portions permitting inversion of the cover portion and partial insertion of the container portion 110 into the cover portion, said portions being formed from a single blank of fibrous material, certain sections of which constitute the bases of the cover and container portions, and other sections of which are bent 115 upon themselves so that opposite walls of one of said portions will be made up of outer and inner sections, the inner of said sections being provided with lateral extensions bearing on the base of said portion, and means comprising a separate sheet of fibrous material insertable into said portion for securing the said extensions against displacement. 120

3. A folding display box comprising telescoping cover and container portions, a flexible connection between said portions permitting inversion of the cover portion and partial insertion of the container portion 125 into the cover portion, said portions being 130

formed from a single blank of fibrous material, sections of which constitute bases of the cover and container portions and other sections of which are bent upon themselves so as to provide opposite walls consisting of outer and inner sections, the inner of said sections being provided with lateral extensions bearing on the base of one of said portions, a separate sheet of fibrous material insertable into one of said portions and adapted for securing the said extensions therein against displacement, other sections of said blank constituting opposite walls of one of said portions and secured to the first-named walls.

4. A folding display box comprising telescoping cover and container portions, and a flexible connection between said portions permitting inversion of the cover portion and partial insertion of the container portion into the cover portion, said portions and connection being formed from a single blank of fibrous material, one section of which constitutes the base of the cover, and other sections of which are bent upon themselves so as to provide opposite walls, said walls consisting of outer and inner sections, the inner of said sections being provided with lateral extensions, a separate sheet of fibrous material insertable into one of said portions, and bearing on the said extensions to prevent displacement of same, one end portion of said sheet being extendable upwardly from one end of said portion and constituting a display panel.

5. A folding display box formed from a plurality of blanks of fibrous material each of which is substantially parallelogrammatic in contour, one of said blanks having a greater surface area than another and provided with intersecting transverse and longitudinal incisions cooperating to provide a container portion, a cover portion, and a tongue or flexible connection between said portions, said tongue being connected at one end to the middle portion of the bottom of the container, so as to fold and thereby permit the cover and container portions to telescope in the closed position of the box, and further to permit inversion of the cover portion and superimposition thereon of the container portion in the display position of the box, said blank further having bendable marginal portions adapted to be connected one to the other and constitute the flanges of the said cover and container portions, one of the flanges of said cover being adapted to intercept one end of the container portion upon inversion of the cover and thereby support the container at an incline to the cover in the display position of the box, another of said blanks being insertable into the container portion and adapted to provide a false bottom therefor and a closure for the opening when the tongue is folded.

6. A folding display box formed from a plurality of blanks of fibrous material each of which is substantially parallelogrammatic in contour, one of said blanks having a greater surface area than another and provided with intersecting transverse and longitudinal incisions cooperating to provide a container portion, a cover portion, and a tongue or flexible connection between said portions, said tongue being connected at one end to the middle portion of the bottom of the container, so as to fold and thereby permit the cover and container portions to telescope in the closed position of the box, and further to permit inversion of the cover portion and superimposition thereon of the container portion in the display position of the box, said blank further having bendable marginal portions, one of the flanges of said cover being adapted to intercept one end of the container portion upon inversion of the cover in the display position of the box, another of said blanks being insertable into the container portion and adapted to provide a false bottom therefor and a closure for the opening when the tongue is folded, said last named blank having an extension at one end interlocked with one of the end flanges of the container and constituting a reinforcement therefor.

7. A folding display box comprising a body and a cover adapted to fit together in the closed position of the box and the box body adapted to fit in an inclined position within the cover in the display position of the box, said body having a section of its bottom wall cut out on lateral lines, said section hinging with respect to the remainder of the bottom wall and also hinging with the adjacent end wall of said cover, said section adapted to rest against said remainder of the bottom wall of said body in the display position of the box, and a supplementary bottom secured in said box body and overlying said hinging section, said supplementary body having a display panel projecting upwardly from the rear portion thereof.

8. A folding display box comprising complementary body and cover sections adapted to fit together in the closed position of the box, said body adapted to be received in an inclined position within said cover in the display position of the box, said body having a section of its bottom wall cut out and having a hinged connection with the fixed part of the bottom wall and also a hinged connection with the upper edge of the adjacent end wall of the cover, said section adapted to contact with and support the rear portion of the bottom wall of the body in the display position, tabs at the end of the box body overlying said section and a supplementary bottom for the body having wall sections bent therefrom and embracing

said tabs, said wall sections being interlocked together upon the tabs.

9. A folding display box comprising a complementary cover and box body adapted to telescope together in the closed position of the box, said body adapted to rest within the cover in an inclined position in the display position of said box, the bottom of the body having a section cut therefrom on two sides and having a crease hinged connection with the remainder of the bottom at its other side and also having a creased hinged connection with the upper edge of the adjacent end wall of the cover, said section being received against the overlying portions of the body bottom in which display position of the box, tabs upon the box body overlying said section, and a supplementary bottom fitted in said box body and having a display panel at one end and a pair of foldable double walls at its other end adapted to extend on opposite sides of the tabs, the end of said supplementary bottom adjacent the double walls being interlocked with said supplementary bottom.

10. A folding display box, consisting of a blank of sheet material, foldable to provide a base portion, side walls having inner and outer sections, said inner sections provided with marginal flanges to extend upon the base portion and having flaps at one of their ends projecting inwardly towards each other, and an end wall at the opposite end

of the base portion, said wall having flaps on its ends extending between the inner and outer sections of the respective side walls, and a false bottom insertable into the folded box and having a foldable portion adapted to coact with said inwardly extending flaps and overlying the marginal flanges on the side walls to retain the several parts of the box blank in proper relative folded positions.

11. A folding display box consisting of telescoping cover and container portions formed from a single blank or sheet material, said blank including a freely movable tongue flexibly connecting the cover portion at one of its ends to the base of the container portion at a point intermediate of its ends and permitting the container portion to be partially inserted within the cover portion and supported by said tongue in a longitudinally inclined position, and a false bottom insertable within the container portion having a foldable part at one of its ends to constitute one end wall of the container portion and provided at its other end with a display panel foldable into substantially parallel relation to the base of said container portion when the latter is nested within the cover portion.

In testimony that we claim the foregoing as our invention, we have signed our names.

JOSEPH B. SINGER.
ARTHUR B. LEVY.
